UNITED STATES PATENT OFFICE.

FREDERICK W. LUEDKE, OF TRENTON, NEW JERSEY.

EXPLOSIVE-TURBINE.

No. 874,693.

Specification of Letters Patent.

Patented Dec. 24, 1907.

Application filed August 15, 1904. Serial No. 220,846.

To all whom it may concern:

Be it known that I, FREDERICK W. LUEDKE, a citizen of the German Empire, residing at Trenton, county of Mercer, and State of New Jersey, have invented certain new and useful Improvements in Explosion-Turbines, of which the following is a specification.

This invention relates to turbines and more especially to that class of turbines which are driven by the expanded vapors derived from the explosion of combustible fluids.

The object of the invention is to accomplish directness of energy conversion producing adiabatic and complete expansion by providing a combustion chamber located in juxtaposition to the exit nozzle, in which the heat energy is converted into kinetic energy. The latter is utilized to drive the turbine wheel.

20 A further object of the invention is the provision of novel means for sucking and compressing the combustible fluid in the combustion chamber.

25 A still further object is the provision of novel means whereby the valve of the exit part is operated to open at a predetermined time and novel means for adjusting the degree of pressure at which the vapors are admitted to the turbine wheel.

30 A still further object is to provide a novel way in which the supply of fluid to the combustion chamber, is cut off, and the advantageous way it is vaporized.

A still further object is the provision of advantageous means for cooling the buckets of the turbine.

Another object is to provide novel means for operating the sparkler.

Having the foregoing objects in view, the invention consists of certain improved features of construction and novel combinations and adaptations of parts set forth hereinafter and recited in the appended claims.

In the drawings:—Figure 1 is a front elevation with parts broken away to better illustrate the way the pistons are operated; Fig. 2 is a side elevation partly in section showing the relation of the explosion cylinders to the turbine wheel and the gearing for operating the pistons. Fig. 3 is a view, partly in section, showing in detail the sparkign means and starting device. Fig. 4 is a sectional view of one of the cylinders showing the piston at the end of its suction stroke and 55 the split ring closing the inlet port, the exit

port or nozzle being closed; Fig. 5 is a sectional view of one of the cylinders showing the piston at the time of explosion, the exit port being open. Fig. 6 shows the piston in the middle of its inward stroke compressing 60 the liquid, the exit port being closed. Fig. 7 shows the piston on the middle of the outward stroke, the fluid port being opened, and before being closed by the ring; Fig. 8 is a diaphragmatic view of the sparkler and magnet; 65 Fig. 9 is a detail plan view of the valve stem catch; and Fig. 10 is an end view of the split ring.

Referring more specially to the drawings, 1 represents the base of the casing 2 which 70 practically surrounds the entire mechanism and which supports the turbine wheel 3, centrally journaled in the casing 2, on main shaft 4. Mounted on the casing 2 and arranged tangentially to the turbine wheel are 75 a plurality of explosion cylinders 5 each provided with a piston 6 and a piston head 7, which is provided with a headed extension 8, and surrounding this extension 8 is a split ring 9. As shown in Figs. 3 to 7 the 80 piston 6 is provided with annular collars 10 and 11, which are adapted to engage a stud pin 12 mounted on the main lever 13. This lever 13 is pivoted to the casing at 14 and is provided at 15 with a relatively long slot 85 which is engaged by a pin 16 rigidly secured to a gear wheel 17 driven by the turbine wheel 3 in any suitable manner. In mesh with the wheel 17 is a pinion 18 provided with a crank 19 and handle 20 which can be 90 used to start the device by hand.

Sliding centrally through the piston 6 is a nozzle- valve-stem 21 provided with the removable cone valve 22 which is adapted to close the exit port 23 in direct communication with the buckets of the turbine wheel by the nozzle 24. This stem is also slidably mounted in a bracket 25 secured to the casing and is provided with an abutment 26, between which and the bracket 25 is mounted a 100 spiral spring 27 adapted to normally force the valve 22 from its seat. Pivoted to the casing at 28 is a trip lever 29 provided, at one end, with a head 30 adapted to be attracted by magnet 31 which will be hereinafter described, and at the other end with a hammer 32 which engages a catch 33. This catch is provided with a spring 34 surrounding its axis which tends to normally throw it into engagement with the abutment 26. A lever 110

35 is pivoted to the casing at 36 and is provided with a leaf spring 37 on its face end adapted to engage the abutment 26 and force it and the valve stem 21 inward when 5 acted upon by the arm 38 which is attached to the lever 35 at one end and at the other end to the main lever 13.

In Fig. 2 there is shown a gear 39 loosely mounted on the main shaft 4 which gear is provided with an eccentric 40. This wheel receives motion from a pinion 41 keyed to a jack shaft 42 and this jack shaft is provided with a gear 43 meshing with a pinion 44 secured to the main shaft. This arrangement 15 allows for the change of gears to regulate the timing of the explosion and the suction and compression. Loosely mounted on the eccentric 40 is a collar 45 having the ears 46 in which an arm 47 is pivoted and pivotally secured to the arm 47 is a lever 48 rigidly secured to a shaft 49 at its opposite end. This shaft is journaled in an extension of the casing and has an arm 50 rigidly secured thereto, which arm is provided with a stud pin 51 25 adapted to engage the collars 10 and 11 on the piston 6. Pivotally secured to the arm 50 is a rod 52 which actuates the valve operating lever 53.

The casing 2 is provided with a divisional plate 2' which separates the turbine wheel from the gearing and in this divisional plate 2' the main shaft 4 and the jack shaft 42 find bearings. A slot 54 is also formed on the plate 2' by two raised flanges, and in this slot 35 a pin 55 integral with the collar 45 is adapted to reciprocate and prevent the collar from turning around its center. The whole running in oil.

Extending out from the casing of the cylinders 5 are two lugs 56 in which a contact rod 57 slides. This rod is provided with collars 58 and 59 the latter of which is adapted to limit the movement of the rod forward and the former acts as an abutment for a coil 45 spring 60 adapted to normally force the rod outward. Two switch points 61 are located adjacent one end of the rod 57 which closes the switch when forced inward by the main lever 13 which as before stated is operated by the turbine wheel. When the contact is made by the rod 57 the current sparks across the point marked *x* and at the same time operates the magnet 31.

On the cylinders 5 are chairs 62 and reciprocally mounted in the center of each is a spring pressed rod 63 which enters a port 64 communicating with the combustion chamber. Leading away from port 64 to the turbine buckets is a muzzle 65 adapted 60 to convey to the buckets the overpressure exhaust.

The cylinders are provided with water or air jackets having the inlet ports 66. The buckets of the turbine wheel are cooled by 65 water from pipes 68. The jackets of all the

cylinders are connected with each other by the casting.

The starting operation is as follows: The wheel 17 is made to revolve one revolution through the gear 18 and hand lever 19, thus 70 the piston in the start of the revolution assumes the position shown in Fig. 7 when $\frac{1}{4}$ of the revolution is made. When $\frac{1}{2}$ of the revolution is made, the piston stands at the position shown in Fig. 4, the split ring 9 having 75 closed the fluid inlet port 69, when $\frac{3}{4}$ of the return revolution is made the piston stands as shown in Fig. 6, the port still being held closed by the ring, and when the full revolution is completed the piston stands as 80 shown in Fig. 5, the piston closing the inlet port. In the first half of the revolution the main lever has retracted the valve stem and seated the exit valve through the lever 35, arm 38 and leaf spring 37. The catch 33 85 now comes into engagement with the head 26 and holds the valve seated until the full revolution is made, when the main lever presses the rod 57 inward to close the switch. When the circuit is complete, the current 90 arcs the points *x* causing a spark and exploding the gases. Simultaneous with the arcing of the current, the magnet 31 is operated to draw up the headed end 30 of the lever 29 and consequently bear down on 95 the opposite end causing the hammer 32 to press the free end of the catch 33 and release it from the head 26. This allows the spring 27 to force the valve 22 away from its seat and let the vapors under high pressure escape. If the pressure is too great before 100 valve 22 is opened, the rod 63 is raised sufficiently against the action of its spring to allow the gases to escape to tube 65 and to the buckets of the turbine wheel. The pre- 105 caution of using this safety is only taken for fear that the valve operating mechanism should not work at the proper time, as ordinarily the valve opens simultaneously with the explosion. Should the magnet fail to 110 perform its function the pressure of the explosion would raise the rod 63 against the headed end 30 of the lever 29 and operate the catch 33 to release the valve 22. The levers shown in Fig. 1 work alternately to cause the 115 suction, compression, and explosion, according to the position of the eccentric 40.

The exhaust from the turbine wheel of water or steam and spent gases is carried off through pipe *y*. 120

What I claim as new and desire to secure by Letters Patent is:—

1. In a device of the class described, the combination with a turbine wheel, of an explosion cylinder having an exit adapted to 125 deliver its charge to the turbine wheel for operating said wheel, means controlling the passage of the exploded charge through said exit to the turbine wheel, and means for exploding a charge within the cylinder, said 130

charge exploding means being adapted to release the means controlling the passage of the exploded charge to the exit.

2. In a device of the class described, the 5 combination with a turbine wheel, of an explosion cylinder having an exit adapted to deliver its charge to said turbine wheel for operating same, a valve closing the exit, means for exploding a charge within the cylinder, said means operating means whereby the valve is released; and auxiliary means adapted to operate the valve should the last mentioned means fail to act.

3. In a device of the class described, the 15 combination with a turbine wheel, of an explosion cylinder having an exit adapted to deliver a charge to the turbine wheel, means controlled by the turbine wheel for closing the exit, means automatically operated by the 20 turbine wheel for releasing said closing means, and auxiliary means operated by the expanded gases of the explosion adapted to release said closing means should the turbine operated means fail to act.

25 4. In a device of the class described, the combination with a turbine wheel, of explosion cylinders having exits adapted to deliver their charges direct to the turbine wheel, valves closing said exits, and automatic electric means controlling the release of said valves at a predetermined time.

30 5. In a device of the class described, the combination with a turbine wheel, of explosion cylinders having exits adapted to deliver their charges direct to the turbine wheel, valves closing said exits, and electrical means operated by the turbine wheel for automatically releasing said valves at a predetermined time.

35 6. In a device of the class described, the combination with a turbine wheel, of explosion cylinders having exits adapted to deliver their charges direct to the turbine wheel, valves sliding in said cylinders for 40 said exits, means operated by the turbine wheel for positively and automatically closing said valves at predetermined times and locking them in closed position, and means for automatically opening said valves at 45 other predetermined times.

50 7. In a device of the class described, the combination with a turbine wheel, of explosion cylinders having exits adapted to deliver their charges direct to the turbine 55 wheel, valves sliding in said cylinders for said exits, means for closing said valves at predetermined times, means for positively locking said valves closed at predetermined times, means for automatically releasing said 60 locking means at the time of the explosion, and means for automatically opening said valves after said locking means has been released.

65 8. In a device of the class described, the combination with a turbine wheel, of explo-

sion cylinders having exits adapted to deliver their charges direct to the turbine and thereby operate same, valves for said exits sliding in said cylinders, means operated by the turbine wheel for automatically closing 70 said valves, means for holding said valves positively closed for a predetermined time, automatic means operated by the turbine wheel for releasing said locking means, and means for opening said valves after said locking means has been released.

9. In a device of the class described, the combination with a turbine wheel, of explosion cylinders having exits adapted to deliver their charges direct to said wheel and 80 thereby operate same, pistons in said cylinders, means operating said pistons to suck in and compress charges, means for exploding the charges, and automatic means operated independently of the turbine for releasing 85 said exploded charge.

10. In a device of the class described, the combination with a turbine wheel, of explosion cylinders having exits adapted to deliver their charges direct to the turbine 90 wheel and thereby operate same, pistons in said cylinders, means operated by said turbine wheel for reciprocating said pistons to suck in and compress charges, means for exploding charges, and automatic means controlled 95 by said exploding means for releasing said exploded charge.

11. In a device of the class described, the combination with a turbine wheel, of explosion cylinders having exits adapted to deliver their charges direct to the turbine wheel, and thereby operate same, pistons in said cylinders, levers operated by said turbine wheel and connected to the pistons for reciprocating said pistons to suck in and 105 compress a charge, means for exploding the charge, and automatic means controlled by said exploding means for releasing said exploded charge.

12. An explosion cylinder having an operable piston, means for holding said piston practically stationary during the explosion, and means operated by said holding means for exploding a charge.

13. An explosion cylinder having a piston, 115 means for operating said piston, said means holding the piston practically stationary during the explosion, and a sparkler, said piston holding means operating said sparkler.

14. An explosion cylinder having a piston, 120 and an exit, means for operating said piston, said means holding the piston practically stationary during the explosion, a sparkler, said piston holding means operating said sparkler, a valve closing said exit, and means 125 operated by said sparkler circuit adapted to open the valve.

15. In an explosion cylinder, having an exit port, the combination with a piston working in said cylinder, of means for oper- 130

- ating said piston, a valve for directly closing said exit port whose stem is slideable within said piston, means for locking said valve closed, and means for releasing said valve locking means.
16. In an explosion cylinder having an exit port, the combination with a piston working therein, of means for operating said piston, a valve for directly closing the exit port in the cylinder whose stem is slideable within the piston, means for locking said valve closed and automatic means for releasing said valve locking means.
17. In an explosion cylinder having an exit, the combination with a piston working therein, of means for reciprocating said piston, means for exploding a charge in said cylinder, a valve for closing said exit sliding within said piston, a catch for holding said valve closed, and automatic means operated by said exploding means for releasing said catch.
18. In an explosion cylinder having an exit, the combination with a piston working therein, of means for reciprocating said piston, means for exploding a charge in said cylinder, a valve for closing said exit sliding within said piston, a catch for holding said valve closed, automatic means operated by said exploding means for releasing said catch, and a resilient member for opening said valve after the catch has been released.
19. In an explosion cylinder having an exit, the combination with a piston working therein, of a lever for reciprocating the said piston, a valve for closing said exit sliding within said piston, a catch for holding said valve closed, a lever adapted to release said catch, automatic means for operating said lever, and a spiral spring surrounding the valve rod and adapted to unseat it after the catch has been released.
20. In an explosion cylinder having an exit, the combination with a piston operable therein, of a lever for reciprocating said piston, a valve for closing said exit sliding within said piston and provided with a head, a catch adapted to engage said head and hold
- said valve closed, a lever adapted to release said catch, a magnet for operating said lever, 50 and a spiral spring surrounding said valve and adapted to unseat it after the catch has been released.
21. In a device of the class described, the combination with a turbine wheel, of an explosion cylinder having an exit adapted to deliver a charge to the turbine buckets, a valve for said exit, a charge inlet to said cylinder, a spark for exploding the charge, a spark circuit, means operated by the turbine wheel for closing said valve, means for locking the valve closed, and means operated by the spark circuit for releasing said valve locking means simultaneously with the explosion.
22. In an explosive engine, the combination with an explosion-operated motor, of an explosion chamber for generating the charge for operating the motor, means controlling the passage of the exploded charge to the motor, means for automatically operating said controlling means at the time of the explosion to permit the exploded charge to pass to the motor, and auxiliary means operated by overpressure in the explosion chamber for 75 operating the said controlling means.
23. In an explosive engine, the combination with an explosion-operated motor, of an explosion chamber for generating the charge for operating the motor, means controlling the passage of the exploded charge to the motor, means for automatically operating said controlling means at the time of the explosion to permit the exploded charge to pass to the motor, and auxiliary means operated by overpressure in the explosion chamber for operating the said controlling means and for permitting the overpressure to bypass to the motor.
- In testimony whereof I hereunto affix my signature in presence of two witnesses.

FREDERICK W. LUEDKE.
